and how long a time it takes to get that garment off the hanger. Well, one of the greatest difficulties in getting a garment off a good hanger is that it is so tightly fastened to the hanger that it is difficult to remove it.

UNITED STATES PATENT OFFICE

2,615,602

GARMENT HANGER AND FORM BOARD

Ernest S. Thompson and Norman A. Weitz,
Atlanta, Ga.

Application April 10, 1950, Serial No. 154,898

1 Claim. (Cl. 223—87)

1

This invention relates to garment hanger and form board improvements.

An important object of this invention is to provide a garment hanger and form board that is readily stamped, cut, or molded from chip board, card board or other suitable sheet material.

A further object of this invention is to provide a structure that readily accommodates both male and female apparel through the steps of manufacturing, packing, and shipping, and eliminates excessive unbuttoning and buttoning, common to standard hangers.

A still further object of this invention is to provide a device that gives the garments supported thereby a tailored, bloused and appealing appearance when used in display.

Various other objects and advantages will be apparent from the detailed description to follow.

The invention is illustrated in the accompanying drawings, wherein:

Figure 1 is a front view of the invention showing a dress mounted thereon;

Figure 2 is a front view of the present invention with the form board in stapled position and the dress assuming a bloused look;

Figure 3 is a front view of Figure 2 but with the hook and garments shown in packing position;

Figure 4 is a vertical sectional view taken substantially along line 4—4 of Figure 3;

Figure 5 is a vertical sectional view of the hanger and board with a garment being held by the slot; and

Figure 6 is a perspective view of the present invention in exploded position with part of the form board broken away.

Referring more particularly to the drawings wherein like numerals designate like parts throughout the figures, numeral 10 generally designates the garment hanger, and 12 designates the form board. Looking at Figures 1 and 6, the garment hanger 10 has a pair of downwardly sloping shoulders 14 upon which the shoulder portions of the garment rest, and a hook 16 is provided to support the entire device. Directly below the hook 16, a slot 18 is stamped to provide a weakened portion whereby the hook may be bent over when desired for shipping purposes.

The main portion of the garment hanger 10 has a center portion cut or stamped out to semi-circular form 20 to provide a hand grip opening. At the extremities of the diameter of the cut

2

out portion 20, a pair of narrow slots 22 are provided and wherein a folded garment is placed with the heavy belt-line seam or trouser cuffs of the garment on one side and the rest of the garment hanging down on the other side, the seam 36 keeping the garment from slipping through, as best shown in Figure 5. The form board 12 is made of suitable length determined by the length of the box into which it is to be placed. Both the garment hanger and form board have all corners rounded to eliminate tearing and snagging common to standard hangers new in use.

Along the center line of the hanger but below the diameter of the cut-out portion, an inverted U-shaped slot 24 is stamped leaving a tongue 26, the tongue 26 is bent to form a hanger peg 28. Upon the hanger peg 28, a form board, indicated generally at 12, is supported. The form board 12 has a slot 30 to receive the tongue 26 of the hanger peg, and a pair of shoulders 32 suitably located on the board to provide means for supporting the garment at the hip portions. After the garment has been placed on the hanger 10, the form board 12 is raised so that the V-grooves 23 and 25 are aligned. The hip portions of the garment will be carried by the shoulders 32 and will give the garment a bloused appearance as at 33. The board is stapled in this position at 34.

Figures 3 and 4 show the hook of the garment hanger folded over for shipping, and the garments on the hanger and board also folded into packing position.

Figure 5 shows a garment in folded position with the heavy seam on one side of the slots 22 and the rest of the garment folded about the form board.

It is believed that from the above description and the drawings various advantages will readily occur to one skilled in the art.

It will be seen that with the garment hanger and form board made separately, each part may be fitted into position in the garment.

By making the invention from sheet material the hangers can be stacked one upon the other, with or without garments, and will not become entangled. By having the cut out portion, a convenient handle is provided which obviates the practice of lifting the hanger and garment by holding the collar and hanger together, which objectionably crushed and soiled the collars.

It will also be seen that the novel folding arrangement will allow compact packing for shipping and storage.

Some changes may be made in the construction and arrangement of the parts of our device without departing from the spirit and scope of the invention covered by our claim.

Having described the invention, what is claimed as new is:

A hanger comprising a sheet of bendable material having a horizontal slot therein for the reception of a garment and further having a notch at an intermediate point in the lower wall of the slot, a form board for suspension from the lower portion of the sheet, said form board having a horizontal slot in its upper portion, said sheet still further having a substantially U-shaped slit in its lower portion defining an integral upstanding, laterally bendable tongue engageable in the second named slot for temporarily suspending the board from the sheet, said board

further having a notch in its upper end for alignment with the first named notch for centering said board on the sheet, and a suspension hook rising from said sheet.
